UNITED STATES PATENT OFFICE

JOHN SNEED, OF FERNDALE, MICHIGAN, ASSIGNOR TO THE MIDLAND STEEL PRODUCTS COMPANY, OF CLEVELAND, OHIO, A CORPORATION OF OHIO

BRAKE ASSEMBLY

Application filed June 18, 1928. Serial No. 286,154

This invention relates to vehicle brakes and particularly to the connection between the expanding mechanism and the brake shoe.

In this brake the spreading mechanism 5 comprises a horizontally disposed toggle, the ends of which engage opposite ends of the brake shoe whereby the ends of the shoe are spread apart during braking engagement. The ends of the toggle do not engage the shoe 10 directly but are carried by laterally extending thrust pins, which pins are supported at their ends, for example, by the side flanges of the channelled end of the shoe. The pins are preferably free to rotate with relation of 15 the side flanges of the shoe to facilitate universal movement between the shoe and the toggle. Heretofore, these pins have been held against lateral movement relative to the shoe by such means as cotter pins.

20 It is among the objects of my invention to secure these pins against lateral movement in the ends of the shoe by means which may be more quickly assembled than the cotter pins and which have greater life and are less 25 susceptible to failure by breakage.

Other objects will appear from the following description of a preferred form of my invention, reference being had to the accompanying drawings. The essential characteristics are summarized in the claims.

30 In the drawings, Fig. 1 is a partial elevation of a shoe including the toggle spreading mechanism; Fig. 2 is a section taken along the line 2—2 of Fig. 1; Fig. 3 is a side 35 view of one of the thrust pins; Fig. 4 is an end view of the same and Fig. 5 is a top view thereof; Fig. 6 is a partially broken section of one of the retaining members before assembly; Fig. 7 illustrates the same member 40 after assembly; and Figs. 8 and 9 illustrate steps in assembling the pins and retaining members.

45 Referring to Fig. 1, there is illustrated a fragmentary elevation including the shoe ends of the brake, which is more fully described in my co-pending application, Serial No. 261,760, filed March 15th, 1928. Briefly my invention may be illustrated in connection with a brake having a brake drum D, a 50 shoe S which is channelled in section at one

end (see also Fig. 2). An anchor pin P is provided against which the shoe ends abut. One of the ends of the shoe may have an adjusting device A with depending spaced ears 5 and 6 as illustrated in my co-pending application.

To spread either end away from the anchor, a toggle T is shown (see also Fig. 2) which toggle may be engaged in its mid-portion by a yoke Y which is drawn by a cable 60 C to flatten the toggle and spread the ends of the shoe apart. The toggle comprises a pair of arms 10 and 11, the ends of which straddle pins 20 which are pivotally mounted in the respective ends of the shoe and extend 65 parallel to the anchor pin. In each of the pins 20, I provide vertically extending pins 22 which are engaged by bifurcated ends of the toggle so that universal movement is provided between the toggle and either end 70 of the shoe. Referring also to Figs. 3, 4 and 5, the upper and lower sides of the pins 20 may be flattened as at 24 so that the toggle arms 10 and 11 may have flattened bearing surfaces on the top and bottom of the pins. 75

The pins 20 may be similar in form and may have reduced end portions 31 with adjacent shoulders 32. An aperture 33 is formed in the side flange of the channel part of the shoe adjacent the anchor through which the reduced 80 end portion 31 of the pin 20 extends so that one end of the pin contacts with the apron as at 34 and the shoulder 32 engages the inner side of the flange of the shoe. The pin, which is carried by the adjusting member, contacts 85 with the apron at 35 and is similarly supported. Thus the pins space the sides of the ends of the shoe from the apron.

Referring particularly to Figs. 3 to 9, the side flange of the channel remote from the apron has an opening 50 with a diameter as great as the greatest diameter of the pin through which the pin may be passed when the parts are assembled. Thus in Fig. 8 the pin is shown with one of the reduced end 90 portions 31 extending through the aperture 33 and with the other reduced end portion lying in the opening 50 but not supported thereby. With the parts in this position the cupped-like member 40 is inserted into the 100

annular space between the reduced end portion 31 and the walls of the opening 50 and from this position is forced or pressed with its brim against the shoulders 32 of the pin so that its brim is flared outwardly as at 41 until it assumes the shape shown in Figs. 2 and 7. Because of the flattened portions 24 on the pins the shoulders 32 may not be uniform (see Fig. 4) and a removable mandrel 60 (see Fig. 9) may be used to facilitate flaring the brim of the retaining members 40.

As illustrated in Fig. 2, similar operation with similar parts secures the other pin between the depending ears 5 and 6 of the adjusting member A. The pins are held at one end by direct contact between the shoulders and the inner sides of the flanges and at the other end by the shoulders acting through the members 40. The retaining members 40 having once been driven to position hold the pins against lateral movement and support the pins while permitting rotation between them and the ends of the shoe.

While the foregoing is a description of the preferred form of my invention, changes within its scope may occur to those skilled in the art and I do not care to be limited to the specific structural details shown or in any manner other than by the claims appended hereto.

I claim:-

1. The combination of a brake shoe having spaced parallel thrust parts with aligned openings therein, a thrust member supported at its ends in said openings, and a retaining member having side walls engaging the wall of one of said openings and having an outwardly flared brim of greater diameter than said opening.

2. The combination of a brake shoe having spaced parallel thrust parts with aligned openings therein, a thrust member supported at its ends in said openings, and a retaining member having side walls engaging the wall of one of said openings and having an outwardly flared brim of greater diameter than said opening, said brim being disposed adjacent the face of one of the parts and in the space between the parts.

3. The combination of a channeled brake shoe having side flanges with aligned openings therein, a thrust pin supported at its ends in said openings and having at least one end portion of less diameter than the diameter of the opening with which it is associated and having shoulders adjacent its reduced end portion and adjacent said opening, and a cup-shaped retaining member overlying said reduced end portion and disposed within said opening and having an outwardly flared brim of greater diameter than said opening lying adjacent said shoulders.

4. In a brake, the combination of a friction device having spaced thrust parts with

aligned openings of different diameter, a thrust pin with reduced end portions of like diameter supported in said openings, one of said end portions closely fitting the smaller of said openings, and a cup-shaped retaining member for the other end of said pin having walls which serve as a bushing between the larger opening and the other reduced end portion and having a brim of greater diameter than the opening for limiting movement of said pin relative to said thrust parts.

5. The combination of a channeled brake shoe having side flanges with aligned openings therein, a thrust pin journaled at its ends in said openings and having at least one reduced end portion of greater length than the thickness of the flange with which it is associated and having shoulders adjacent its reduced end portion bearing on the inner face of the flange whereby part of the reduced end portion extends beyond the side of the flange and constitutes a steady rest for the shoe.

6. In a brake, the combination of a friction device having spaced thrust parts with aligned openings, a thrust pin with at least one reduced end portion longer than the thickness of the thrust parts and pivotally mounted in one of said openings and extending beyond the face of said thrust part and comprising a steady rest for the friction device, and means for securing the other end of said pin in the other of said openings and holding it against longitudinal movement relative to said thrust parts.

7. In a brake, the combination of a friction device having spaced parallel thrust parts with aligned openings of different diameter, a thrust pin having reduced end portions of like diameter supported in said opening, said pin having shoulders adjacent its reduced end portions, one of said reduced portions fitting in one of said openings with the shoulders of the pin lying against one of said thrust parts, the other of said reduced end portions extending in the greater of said openings and spaced from the walls thereof with the shoulders of said pin spaced from the face of the other of said thrust parts and a cup-shaped retaining member having its inner walls engaged by the last named reduced end portions and having its outer walls closely fitting in said last named opening and having its brim flared outwardly against said last named shoulder to a greater diameter than said opening.

8. The combination according to claim 7 wherein the larger of said openings has a diameter substantially equal to the greatest diameter of said pin whereby the parts may be assembled by first passing said pin through the greater of said openings.

9. In a brake, the combination of a friction device having spaced parallel thrust parts with aligned openings of different diameter,

- a thrust pin having reduced end portions of like diameter and different length and supported in said opening, said pin having shoulders adjacent at least the longer of said reduced end portions, the longer of said reduced portions fitting in one of said openings with the shoulders of the pin lying against one of said thrust parts and extending beyond the friction device and comprising a steady 5 rest therefor, the other of said reduced end portions extending in the greater of said openings and spaced from the walls thereof, and a cup-shaped retaining member having its inner walls engaged by the last named reduced end portions and having its outer walls closely fitting in said last named opening and having its brim flared outwardly against the inner face of the thrust part to a greater diameter than said opening.
- 10 10. In a brake, the combination of a friction device having spaced inwardly extending thrust parts, a laterally extending thrust pin pivotally mounted in said parts, one end of said pin being pivotally mounted in one of said parts and the other end of said pin being pivotally secured in the other of said parts, and a retaining member for securing said last named end having a cup-shaped body and an outwardly flared brim, the brim being formed 15 when the member is pressed onto said pin and having a greater diameter than the body of said pin.
11. In a brake, the combination of a friction device having spaced inwardly extending thrust parts with aligned openings, a laterally extending thrust pin carried by said parts, one end of said pin being pivotally mounted in one of said parts and the other end of said pin being secured in an opening 20 in the other of said parts, said pin being of substantially the same diameter as the opening, and a retaining member for securing said last named end having a cup-shaped body and an outwardly flared brim, the brim being formed when the member is pressed onto said pin and having a greater diameter than the opening.
12. In a brake, the combination of a shoe having inwardly extending side flanges with aligned openings, a thrust pin having its ends supported in said openings, said thrust pin having shoulders at one end bearing against the inner face of one of said side flanges and a cup-shaped retaining member for the other 25 end of said pin adapted to be forced over the end of said pin and deformed while being forced over the end of the pin to engage the inner side of the other of said flanges, the bottom of said cup-shaped member engaging the other end of said pin and holding said shoulders against the inner side of said first named flange.
13. In a brake having an apron and a shoe with parallel inwardly extending side flanges 30 having aligned openings, one of said side flanges lying adjacent to the apron and the other being remote therefrom in combination with a thrust pin supported at its ends in the openings of said flanges and having one reduced end portion, extending through one of said openings and beyond the side of the shoe and into contact with said apron for spacing the shoe from the apron, and a retaining member for the other end of said member having walls acting as a bushing within the opening of the other side flange and a part deformed when the retaining member is forced over the end of the thrust pin to a greater diameter than said opening and supporting the adjacent end of said pin and holding the other end of said pin in contact with said apron and spacing the shoe from the apron.
14. In a brake having an apron and a shoe with parallel inwardly extending side flanges 35 having aligned openings, one of said side flanges lying proximate the apron and the other being remote therefrom in combination with a thrust pin supported at its ends in the openings of said flanges and having one reduced end portion extending through one of said openings and beyond the side of the shoe and into contact with said apron for spacing the shoe from the apron and having shoulders engaging said flange to limit the spacing, and a retaining member for the other end of said member lying within the opening of the other side flange with a part deformed when the retaining member is forced over the end of said pin to a greater diameter than said opening and supporting the adjacent end of said pin and holding the shoulders at the other end of said pin in contact with the first named side flange and spacing the shoe from the apron.
15. In testimony whereof, I hereunto affix my signature.
- JOHN SNEED.
